CLAIM

The ornamental design for a stroller, as shown and described.

DESCRIPTION

FIG. 1 is a front, right, and top perspective view of a stroller, according to a first embodiment of our new design;

FIG. 2 is another front, right, and top perspective view of the stroller of FIG. 1, showing a configuration where a handle is in an upward position;

FIG. 3 is another front, right, and top perspective view of the stroller of FIG. 1, showing a configuration where the handle is in a downward position;

FIG. 4 is a front elevation view the stroller of FIG. 1;

FIG. 5 is a rear elevation view of the stroller of FIG. 1;

FIG. 6 is a left side view of the stroller of FIG. 1;

FIG. 7 is a right side view of the stroller of FIG. 1;

FIG. 8 is a top view of the stroller of FIG. 1;

FIG. 9 is a bottom view the stroller of FIG. 1;

FIG. 10 is a front, right, and top perspective view of a stroller, according to a second embodiment of our new design;

FIG. 11 is another front, right, and top perspective view of the stroller of FIG. 10, showing a configuration where a handle is in an upward position;

FIG. 12 is another front, right, and top perspective view of the stroller of FIG. 10, showing a configuration where the handle is in a downward position;

FIG. 13 is a front elevation view of the stroller of FIG. 10;

FIG. 14 is a rear elevation view of the stroller of FIG. 10;

FIG. 15 is a left side view of the stroller of FIG. 10;

FIG. 16 is a right side view of the stroller of FIG. 10;

(Continued)

FIG. 17 is a top view of the stroller of FIG. 10;
FIG. 18 is a bottom view of the stroller of FIG. 10;
FIG. 19 is a front, right, and top perspective view of a stroller, according to a third embodiment of our new design;
FIG. 20 is another front, right, and top perspective view of the stroller of FIG. 19, showing a configuration where a handle is in an upward position;
FIG. 21 is another front, right, and top perspective view of the stroller of FIG. 19, showing a configuration where the handle is in a downward position;
FIG. 22 is a front elevation view of the stroller of FIG. 19;
FIG. 23 is a rear elevation view of the stroller of FIG. 19;
FIG. 24 is a left side view of the stroller of FIG. 19;
FIG. 25 is a right side view of the stroller of FIG. 19;
FIG. 26 is a top view of the stroller of FIG. 19; and,
FIG. 27 is a bottom view of the stroller of FIG. 19.
The broken (dashed) lines show portions of the stroller that form no part of the claimed design.
